UNITED STATES PATENT OFFICE.

ELLA FRANCES DE FOREST, OF NEW CANAAN, CONNECTICUT.

ATTACHMENT FOR BRASSIÈRES.

Application filed November 30, 1921. Serial No. 518,859.

To all whom it may concern:

Be it known that I, ELLA F. DE FOREST, a citizen of the United States, and a resident of New Canaan, in the county of Fairfield and State of Connecticut, have invented a new and Improved Attachment for Brassières, of which the following is a description.

The general object of my invention is to provide an attachment to be applied to a brassière strap and to the body of the brassière and arranged to make impossible the lateral displacement of the straps over the shoulders of the wearer.

The nature of the invention and its distinguishing features and advantages will clearly appear as the description proceeds.

Reference is to be had to the accompanying drawings forming a part of this specification, it being understood that the drawings are merely illustrative of one example of the invention.

Figure 1 is a perspective view of a brassière having my attachments applied to the straps thereof, the view showing the garment when worn;

Figure 2 is a side elevation of the strap and the upper portion of the brassière with my attachment in position thereon;

Figure 3 is a face view of one of the attachments, parts being broken away;

Figure 4 is a fragmentary face view showing the upper portion of the attachment and the adjacent portion of a strap.

In carrying out my invention in practice in accordance with the illustrated example, I provide an elongated thin strip or elongated plate 10, advantageously formed in practice of springy metal, and having a foot or L-extension 11, the body of the plate being adapted to lie beneath and extend along the front portion of the brassière strap A while the extension is disposed laterally at the upper edge of the brassière B.

Provided on the plate 10 at its upper end and extending upwardly beyond the same is a securing tab 12 preferably of fabric. Similarly, at the lower end of the plate I

provide a fastener tab 13 extending along the extension 11 below the lower edge thereof. The tabs 12 and 13 are adapted to receive suitable fastener pins C, the one fastening the upper end of the spring to the strap A and the other securing the spring to the body of the garment B at the lower end of the strap.

The tabs, 12 and 13, may, as shown, be formed integral with a casing 14 of fabric enclosing the plate and extending laterally as at 14^a over the extension 11.

The above-described attachment effectively prevents the displacement of the straps and at the same time affords no discomfort to the wearer of the garment.

I would state in conclusion that while the illustrated example constitutes a practical embodiment of my invention, I do not limit myself strictly to the exact details herein illustrated, since, manifestly, the same can be considerably varied without departure from the spirit of the invention as defined in the appended claims.

Having thus described my invention, I claim:

1. A device to prevent the lateral displacement of a brassière strap, said device consisting of a plate adapted to lie along the strap and formed with a laterally disposed branch at its lower end adapted to be positioned at the upper edge of the brassière, said spring having a casing extending at its upper end in the form of a securing tab beyond the spring, the casing extending laterally over the branch of the spring and forming an elongated securing tab disposed below the lower edge of said branch.

2. An attachment for brassières consisting of a substantially stiff L-shaped strip, one arm of which is adapted to be disposed vertically in association with a brassière strap, and fabric tabs on the arms of the strip to secure the arms respectively to the body of the brassière and to a brassière strap.

ELLA FRANCES DE FOREST.
